UNITED STATES PATENT OFFICE.

HENRY A. BURLEY, OF MILWAUKIE, OREGON.

WASHING-MACHINE.

1,247,368.

Specification of Letters Patent. Patented Nov. 20, 1917.

Application filed January 16, 1917. Serial No. 142,613.

To all whom it may concern:

Be it known that I, HENRY A. BURLEY, a citizen of the United States, and a resident of Milwaukie, in the county of Clackamas and State of Oregon, have invented certain new and useful Improvements in Washing-Machines, of which the following is a specification.

My invention relates to washing machines, and the main object thereof is to provide means for agitating or pounding articles being washed automatically actuated by the generation of steam in the apparatus; another object is to provide a safety device which directs excess steam into the clothes receptacle; another object is to provide adjustable means for automatically controlling the distance of movement of the pounder; and another object is to provide a float valve in the pounder operating means to prevent the entrance of air into said means when raised to its upward limit.

My invention is fully described in the following specification, of which the accompanying drawings form a part, in which like characters refer to like parts in each of the views, and in which:

Figure 1 is a central vertical section taken through a preferred embodiment of my invention, on the line 1—1 of Fig. 3;

Fig. 2 is an end elevation thereof, from the left hand side of Fig. 1;

Fig. 3 is a top plan view thereof;

Fig. 4 is a fragmentary section taken on the line 4—4 of Fig. 3;

Fig. 5 is a section taken on the line 5—5 of Fig. 4; and

Fig. 6 is a detached view of a lever which I employ.

Referring to the drawings, 7 represents a boiler of the usual household type, although not limited thereto, having a horizontal partition 8 forming compartments 9 and 10, said partition preferably consisting of two metal plates having an asbestos sheet therebetween, the upper compartment 9 being for the reception of the articles to be washed and the lower compartment 10 being the steam generator and having a water inlet pipe 11 leading thereto and extended above the boiler 7, and having a steam outlet 12 open at all times.

The top of the inlet pipe 11 has a conical

casing 13 thereon provided with a spout 14 directed into the boiler 7 and capped by a 55 filler funnel 15 leading downward into the casing 13 adjacent the port 16 connecting the casing and spout, a valve 17 being provided in the bottom of the casing adapted, under steam pressure, to rise and close the 60 lower end of the funnel and thus prevent the escape of steam through the latter whereby a person might be scalded, as in pouring water into the funnel when the compartment 10 is entirely or nearly empty so 65 as to uncover the lower end of the inlet pipe 11.

Joined to the boiler 7 is a container 18, open at its top, for a float 19 of air-tight form having a tube 20 arranged at one side 70 thereof closed at its top and open at its bottom for the reception of a pipe 21 leading from the steam outlet 12 of the generator compartment 10, this construction permitting free vertical movement of the float while 75 preventing the escape of the pipe 21 from the tube 20 and, in a measure, guiding the float in its vertical movements. Said float has a centrally arranged exhaust pipe 22 leading therethrough capped by a bell 23 80 and the lower end of which pipe 22 extends a considerable distance below the float for a reason to be explained, and a pressure vent tube 24 also extends through the float closely adjacent the pipe 22.

Surrounding the lower ends of the pipe 22 and tube 24 is a dependent flange 25 having a spider connection with a cup 26 provided with a port 27 in its bottom adapted to be closed by a cork valve 28 held in a cage 29, said valve being preferably inclosed in a light metal sheathing to maintain its shape under pressure. The float 19 is provided with legs shown as a dependent flange 30 to limit downward float movement, and I 90 may also provide an air-vent 31 at the top of the float.

Secured to the boiler 7 and container 18 is a shelf 32 having bearings thereon for a shaft 33 upon which are secured two arms 100 34 and 35, the former leading directly over the center of the float 19 and resting in a saddle 36, and the latter being extended over the boiler 7, said arms being simultaneously moved in the rocking of the shaft 33, and 105 the outer end of the arm 35 is slotted at 37.

Arranged above the boiler 7 and preferably detachable therefrom is a frame 38, serving as a guide for a vertically movable bar 39 carrying a plunger 40 at its lower end and which, in turn, is provided with pins 41, a coil spring 42 tending to maintain said plunger in lowermost position, and a plate 43 is provided in the bottom of the compartment 9 to take the impact of the plunger hereinafter referred to as the pounder.

Detachably held in the slot 37 of the arm 35 is a lever 44 provided with a slot 45 through which the bar 39 is passed, and in which it is normally slidable, said lever being bent so that upward strain on the arm 46 of the lever will cause the slotted portion to bind against the bar 39 to raise the latter with said lever, a counterweight 47 being provided to assist in this bar arrangement.

Adjustably mounted on the frame 38 is a trip 48 arranged in the path of movement of the lever arm 46 when carried upwardly by the slotted arm 35 in the rocking of the shaft 33 by the upward movement of the float 19 and, when the lever arm 46 strikes the trip, the slotted portion of the lever 44 is carried upwardly until the binding engagement with the bar 39 is overcome and the latter is forced downwardly by the spring 42, the lever 44 sliding freely downward in the downward movement of the slotted arm 35 due to the lowering of the float 19 and, if desired, this downward float movement may be made positive by means of a coil spring 49.

In practice, the frame 38 is removed from the boiler to remove the pounder 40, the lever arm 46 being readily detached from the slotted arm 35 to permit this, after which the articles to be washed are placed in the boiler on the false bottom 43 and the pounder and frame 38 are returned to normal positions with the lever arm 46 again engaged by the slotted arm 35.

Water is now poured into the funnel 15 and float container 18, and suds placed in the clothes compartment 9, the machine being already in position over a source of heat or it may now be placed thereover, with the result that steam is generated in the compartment 10 and passes to the tube 20 and thence to the under side of the float 19 to raise the latter until the lower end of the exhaust 22 is raised above the water level in the container 18 at which time the steam rushes out of the machine and, the pressure within the compartment 10 being now reduced, the float 19 returns to lowered position either by gravity or, if provided, by means of the spring 49.

This upward float movement rocks the shaft 33 and thus causes the slotted arm 35 to rock the lever 44 to bind against the bar 39 and thereby lift the pounder 40 until the trip 48 releases the said bar and pounder

to permit the latter to drop and thereby force the pins 41 into the mass of articles being washed and, as soon as a sufficient pressure of steam is developed, this operation is repeated.

The generation of steam is continuous but the pressure varies because of the periodical exhaust and my machine takes advantage of this variation of pressure, the machine working with all the regularity of a steam engine as long as water and heat are supplied.

It will be obvious that, when the float is at its upper limit of movement, air might pass through the port 27 which is then above the water level but, the valve 28 being a float, said port is closed although it permits the escape of water from the cup in the upward movement thereof with the float, and it is important that the clearance between the end of the exhaust pipe and the bottom of the cup be sufficient to allow the steam free passage up said pipe before the cup is quite empty of water, as the sheet of water between prevents displacement of the valve by the siphon effect of the steam in its rush up the exhaust pipe. The bottom of the cup is preferably rounded slightly downward to the valve to give quick clearance of the end of the pipe by reason of the reduced amount of water contained in the bottom of the cup.

The pressure vent tube 24 and the flange 25 are very important features of the float inasmuch as when the float is down the water closes the end of the exhaust pipe and, the steam outlet being thus closed, the float has a tendency to rise before the valve cup fills enough to raise the water level in the exhaust pipe to correspond with the water level in the float container which is nearly to top of float when the machine is working under full load, and if the water is all taken out of the cup before the float is raised the steam blows out and no stroke is made.

The flange 25 is set to project downward to the level of the cup 26 or slightly below the same and, when the float sinks low enough for the water to run over the top of said cup, the flange 25 also reaches the water level from above and shuts off the connection between the cup and the steam chamber surrounding the flange 25. The pressure vent 24 then allows the pressure within the cup to fall to much less than the pressure in said steam chamber and, as the pressure gradually rises for the next stroke of the float, the water is forced in over the top of the cup 26 to immediately fill the same, and forms a water seal for the exhaust pipe 22 until the float has risen sufficiently high to raise the lower end of the pipe 22 above the water level. The pounder 40 has been raised in this upward float movement and the steam

is exhausted through the pipe 22 permitting the float to again fall, the valve 28 preventing the entry of water into the cup 26 in this downward float movement but, when the 5 water seal is again formed by the steam pressure forcing water over the top of said cup, said float is again forced upwardly, the water escaping from the cup in such upward float movement.

10 At 50 I have shown a lead for the water from the container if forced too high therein, this excess water passing into the boiler compartment 9, and I prefer to provide a heat insulating inclosure for the said container, the heat insulating partition 8 preventing overheating of the water and suds in the compartment 9.

While I have shown an entirely operative structure, it will be obvious that many 20 changes in the details may be made, provided such changes do not depart from the spirit of the invention, and come within the scope of the appended claims.

Having fully described my invention, what 25 I claim as new, and desire to secure by Letters Patent, is:—

1. A washing machine, comprising a vessel, a heat insulating partition therein dividing the same into an upper clothes compartment 30 and a lower steam generating compartment, a pounder in said clothes compartment, means exteriorly of the clothes compartment and operable by the generated steam to intermittently move said pounder 35 in one direction, and means for moving said pounder in the other direction into normal position.

2. A washing machine, comprising a vessel divided into a clothes compartment and 40 a steam generating compartment, a clothes pounder in said clothes compartment, means exteriorly of the clothes compartment and steam generating compartment operable by the generated steam for intermittently raising 45 said pounder, and means operated by said exterior means to permit lowering said pounder after each raising operation.

3. A washing machine, comprising a vessel divided into a clothes compartment and 50 a steam generating compartment, a clothes pounder in said clothes compartment, a vertical bar thereon, a slotted lever thereon adapted to engage the same when said lever is raised and to release the same when said 55 lever is lowered, means operable by the generated steam for intermittently raising said lever and engaged bar, means for adjustably depressing said lever to release said bar, and means for returning said bar and connected 60 pounder to lower position after such release.

4. A washing machine comprising a vessel divided into a clothes compartment and a steam generating compartment, a clothes pounder in said clothes compartment, a float 65 container connected with said steam com-

partment, a float in said container, adapted to be raised and lowered by variations of pressure in said steam compartment, clutch means operably connecting said float and the clothes pounder, and means for actuating 70 said clutch to release the pounder at a predetermined height of the float.

5. A washing machine, comprising a vessel divided into a clothes compartment and a steam generating compartment, a clothes 75 pounder in said clothes compartment, a float container connected with said steam generating compartment, a float in said container, said float being adapted to be raised and lowered by variation of pressure in said steam generating compartment, and means for suddenly exhausting said steam when said float has reached a predetermined height, said float being operatively connected with said pounder. 80

6. A washing machine, comprising a vessel divided into a clothes compartment and a steam generating compartment, a clothes pounder in said clothes compartment, a float container connected with said steam generating compartment, a float therein in operative connection with said pounder and adapted to be raised by steam pressure thereunder, an exhaust pipe in said float, and a water seal for the lower end thereof rendered inoperative when said float has reached a predetermined height to permit the lowering of the steam pressure through 95 said exhaust pipe.

7. A washing machine, comprising a vessel divided into a clothes compartment and a steam generating compartment, a clothes pounder in said clothes compartment, a float container connected with said steam generating compartment, a float in said container 100 in operative engagement with said pounder and adapted to be raised by steam pressure thereunder, an exhaust pipe passed through said float and extended a predetermined distance below the same, said container having water therein into which said exhaust pipe may extend, a cup surrounding the lower end of said exhaust pipe, below the bottom of said float, having a port in its bottom, a caged float valve for said port, and a flange 105 on the bottom of said float, surrounding said exhaust pipe and cup, and extending downwardly approximately to the top of said cup. 110

8. A washing machine, comprising a vessel divided into a clothes compartment and a steam generating compartment, a clothes pounder in said clothes compartment, a float container connected with said steam generating compartment, a float in said container 115 normally held above the level of the water in said container, in operative connection with said pounder, and adapted to be raised by steam pressure thereunder, an exhaust pipe passed through said float and extending 120

125

a predetermined distance below said float, a cup surrounding the lower end of said pipe with its top below said float and ported in its bottom, a float valve for said port, a dependent flange on the bottom of said float surrounding said cup and extended downwardly to approximately the top of said cup,

and a pressure vent pipe passed through said float having its lower open end within said flange.

HENRY A. BURLEY.
